(57) CLAIM

The ornamental design for a hair twist package, as shown and described.

DESCRIPTION

FIG. 1 is front, top, left perspective view of a hair twist package showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is another front, top, left perspective view thereof; and, FIG. 9 is another front, top, left perspective view thereof.

In the drawings, the broken lines are for the purpose of illustrating environment only and form no part of the claimed design.
